UNITED STATES PATENT OFFICE.

SAMUEL LIPSIUS, OF NEW YORK, N. Y.

POWDERING MACHINE.

Application filed April 10, 1924. Serial No. 705,415.

The main object of my invention is to provide a simple and reliable mechanism for applying powder to sheets of paper, etc., for instance, in the art of raised printing. In 5 this type of work the pattern, design, or wording is printed on the paper or other material with a special ink or other composition, which remains somewhat tacky for a short time. While the composition is 10 tacky, powder is applied, which is subsequently fused to provide the permanent raised effect. I have sought to provide mechanism for automatically handling the sheets of paper or the like, applying powder to 15 the sheet, removing the excess powder from those portions of the sheet to which it is not desired to adhere, and then delivering the sheet to be dried, or baked, as the case may be.

20 One object of the invention is to produce neat and uniform effects without wasting powder.

Another object is to prevent the wasteful and unpleasant scattering of the powder.

25 Another object is to provide a simple and inexpensive powdering machine which can be used with an ordinary printing press so as to receive the sheets automatically as they are delivered from the printing press, apply 30 the powder, and feed the sheets rapidly to the baking machine, or oven.

Another object is to construct the powdering machine so that it can be readily adapted 35 to co-operate with the printing press, or disconnected readily from the press so that the printing press can be used independently of the powdering machine.

Another object is to provide a construction 40 which will facilitate the handling of sheets of different sizes as they come from the printing press without danger of turning them over.

Another object is to insure the uniform 45 passage of the sheets through the powdering machine without having the sheets interfere with each other or becoming clogged in the machine.

In carrying out my invention I provide a 50 special type of drum, or revolvable casing, through which the sheets are fed and by means of which the powder is applied. The sheets are fed through this drum by a conveyor consisting of a series of sections of wire mesh, or belts, operated automatically 55 as the drum rotates. One end of this conveyor is so constructed as to adapt it to be

readily connected to or associated with the delivery bed of a more or less standard type of printing press.

Figure 1 is a plan view and partial horizontal section of a machine embodying improvements of my invention. 60

Figure 2 is a side view of the same, showing a part of the conveyor in section as associated with the delivery of a "Miller feeder" on an ordinary printing press. 65

Figure 3 is a side view and partial longitudinal section view on a somewhat larger scale.

Figure 4 is a plan view and partial section 70 on the general plane of the line 4—4 of Figure 2, showing the driving motors and shafts and connected belts or chains.

Figure 5 is a vertical transverse sectional view on the plane of the line 5—5 of the 75 Figure 2.

The drum is preferably of sheet metal and suitably supported, for instance, by pairs of rollers, 11—11, at one end and 12—12 at the other end. The drum is also preferably 80 supported intermediate of its ends by a sort of guide pulley 13 which is driven by a motor 14. The opposite ends of the drum are tapered or conical with a channel or gutter 15 intermediate their large ends. This gutter is provided with a series of small partitions or buckets 16 adapted to pick up and carry around the powder which is placed in the gutter. These buckets may be of any suitable size or number. They may be made 90 in one strip and removable, if desired, so that a greater or less number of buckets may be used for any particular type of work that may be required. I also prefer to provide a tapered hopper or guiding chute 17 95 extending across the drum above the sheets so as to confine the powder as it is dropped from the ascending and descending buckets.

The conveyor consists of a series of sections 20, 21, 22, and 23, constructed and arranged so as to properly receive and transport the sheets of paper or other stock which is to be powdered. These different sections or portions of the conveyor are all preferably driven at uniform speed by some suitable motor 24 with chains, belts, or cords, and pulleys, which engage the shafts 25, 26 and 27 for driving the conveyor 20; shaft 28 for driving conveyor 21; shaft 29 for driving pulley and shaft 30 and conveyor 22. So far as the powdering mechanism per se is concerned it would be under 100 105 110

stood that the printed or prepared sheets might be deposited directly upon conveyor 20 or upon conveyor 21 by hand or in any other way. For high speed and economical 5 operation, however, I prefer to adapt the mechanism to be associated directly with a printing press so as to avoid the necessity of any intermediate handling and loss of time. This also makes it possible to use 10 a more quickly drying ink without losing the effective stickiness required for proper adhesion of the powder. 32 indicates a fragment of the bed or delivery plate of an ordinary printing press, and 33 represents 15 the oscillating arm with the proper grasping jaws 34 for handling the stock sheet 35. In the form shown, the arms 36 which support the conveyor 20 are bent at an angle at their receiving ends so as to correspond 20 with the shape of the delivery bed of the printing press, and intermediate guides or rolls 37 are provided for the conveyor so as to give this end of the conveyor an inclined or angular disposition to accommodate 25 the natural falling angle of the printing sheet 35. I also provide an angular stop 38 adapted to serve as an abutment for the lower edge of the sheet 35 as it is deposited so as to prevent that edge from 30 touching the conveyor before the upper edge of the sheet 35 strikes the conveyor. If the lower edge of the sheet were allowed to touch the conveyor before the upper edge of the sheet, the conveyor would be likely to 35 turn the sheet over and thus spoil the work. To bring the abutment 38 into the proper position for the particular sheet which is being handled, I provide some convenient form of adjustment device, such as adjustable screws 39. I also provide a stop 40 which extends across the conveyor adapted to serve as an abutment to prevent the sheet 35 from sailing too far forward and thus being displaced on the conveyor. The arms 45 36 are preferably hinged about the axis of the shaft 27 so as to permit the conveyor 20 to be tilted up out of the way of the printing press. I have found that conveyor 20 operates much more satisfactorily if its bearing surface is of cloth or similar material, such as canvas, to which the paper 50 more satisfactorily adheres as it is deposited upon the inclined receiving end at the press.

Beneath the entrance and exit ends of 55 the conveyor, I preferably provide stationary guides 42 and 43 respectively, for collecting any powder which may have escaped from the opposite ends of the powdering drum, and re-depositing this powder into the drum where the rotating movement causes the powder to gradually work down to the bottom of the gutter, where the lift buckets are located.

As the printed sheets are carried along 60 by the conveyor 20, they pass automatically

on to the conveyor 21 upon which they receive the powder from the hopper 17. These conveyors 21 and 22 may conveniently be made of helically interwoven wires which form very flexible and durable belts through 70 which the escaping powder may readily pass. As the printed sheet leaves the conveyor 21 it rides up the inclined conveyor 22 to which it is held or in a sense geared by the loosely mounted rotating rings 44 75 and 45. These feed rings are carried by brackets 46 which are preferably adjustable up and down and horizontally so as to facilitate their proper location with respect to the conveyor 22 and the sheets thereon. As 80 the sheets are conveyed up the incline they are vibrated in some suitable manner so as to shake off the powder from the unprinted portions of the sheet. This vibration may be conveniently affected by means of a plate or sort of hand 47 beneath the conveyor 22 which is operated by a crank shaft 48 driven by the pulley 49. This plate 47 may be perforated or constructed in some suitable way so as to permit powder to pass through 85 it and not accumulate upon it. I may also provide any suitable and well known form of suction device for holding the sheets on the conveyor 22, if desired, particularly at that portion which is above the vibrator 47. 90

The delivery end of conveyor 22 may be raised or lowered so as to change the angle of inclination of that conveyor.

It is preferable that those portions of the 100 apparatus which are the most subjected to being powdered should be movable as the powder is of such a nature that it adheres to anything which is stationary and rapidly collects. This only wastes the powder, 105 which is quite expensive.

My present invention constitutes improvements over the construction of my former Patents Nos. 1,144,303 and 1,391,743, and such other construction as I am aware 110 of in features hereinafter set forth in the claims.

I claim:

1. A powdering machine comprising a rotating drum having means for lifting powder and a conveyor for carrying printed sheets through said drum.

2. A powdering machine comprising a rotating drum having means for lifting powder and a conveyor for carrying printed sheets through said drum, one part of the conveyor being of canvas and inclined for receiving sheets as delivered from a printing press.

3. A powdering machine comprising a rotating drum having means for lifting powder and a conveyor for carrying printed sheets through said drum, one part of the conveyor being hinged adjacent to the drum.

4. A powdering machine comprising a rotating drum having means for lifting pow- 120

der and a conveyor for carrying printed sheets through said drum, a portion of the conveyor within the drum being upwardly inclined toward the discharge end.

5. In a powdering machine, a rotating drum, a conveyor for taking sheets through said drum, and means for vibrating a portion of said conveyor within said drum.

6. In a powdering machine, a drum having an annular gutter with a tapered wall leading to said gutter and a conveyor for taking sheets through said drum.

7. In a powdering machine, a drum having a gutter with walls tapered in opposite directions from said gutter, and a conveyor for carrying sheets through said drum.

8. In a powdering machine, a rotating drum tapered at its opposite ends and having a powder-receiving channel between its tapered ends, a conveyor section for feeding sheets into said drum, and a second conveyor section for receiving sheets from the first conveyor section and delivering them from said drum.

25 9. In a powdering machine, a rotating drum tapered at its opposite ends and having a powder-receiving channel between its tapered ends, a conveyor section for feeding sheets into said drum, and a second conveyor section for receiving sheets from the first conveyor section and delivering them from said drum, and means for vibrating the sheets on said latter conveyor section.

10. In a powdering machine, a drum 35 tapered at its opposite ends, a conveyor section for feeding sheets into said drum, and a second conveyor section for receiving sheets from the first conveyor section and delivering them from said drum, and loosely 40 mounted rollers for holding the sheets on said latter conveyor section.

11. In a powdering machine, a drum 45 tapered at its opposite ends, a conveyor section for feeding sheets into said drum, and a second conveyor section for receiving sheets from the first conveyor section and delivering them from said drum, and station-

ary guide chutes extending from the outer ends of said conveyors to within the ends of said drum.

50 12. In a powdering machine, a rotatable drum, a conveyor section for carrying sheets into said drum, and a second and upwardly inclined conveyor section for carrying the powdered sheets from the first conveyor section within said drum.

55 13. In a powdering machine, a rotatable drum, a conveyor section for carrying sheets into said drum, and a second upwardly inclined conveyor section for carrying the powdered sheets from the first conveyor section within said drum, and means for vibrating said inclined conveyor section.

60 14. In a powdering machine, a rotatable drum, a conveyor section for carrying sheets into said drum, and a second upwardly inclined conveyor section for carrying the powdered sheets from the first conveyor section within said drum, and means for holding sheets onto said inclined conveyor section.

65 15. In a powdering machine, a drum tapered at its opposite ends, a roller engaging said drum to rotate the same, and a conveyor for carrying sheets through said drum.

70 16. In a powdering machine, a drum tapered at its opposite ends, a series of rollers for supporting the opposite ends of said drum, means engaging the intermediate portion of said drum for rotating same, and a conveyor for carrying sheets through said drum.

75 17. In a powdering machine a conveyor consisting of a canvas section for receiving sheets from a printing press and a wire mesh section for receiving sheets from said canvas section, a rotating drum surrounding a part of the wire mesh section of the conveyor for depositing powder on sheets on said conveyor, means for removing excess powder from said sheets and means for removing the powdered sheets from said drum.

SAMUEL LIPSIUS.
